UNITED STATES PATENT OFFICE

144,468

DESIGN FOR A WHEELED TOY

Earl J. Reiff, Alliance, Ohio

Application July 21, 1945, Serial No. 120,862

Term of patent 3½ years

(Cl. D34—15)

To all whom it may concern:

Be it known that I, Earl J. Reiff, a citizen of the United States, residing at Alliance, in the county of Stark and State of Ohio, have invented a new, original, and ornamental Design for a Wheeled Toy, of which the following is a specification, reference being had to the accompanying drawing, forming part thereof.

Fig. 2 a front elevation of the wheeled toy shown in Figure 1;

Fig. 3 is a side elevation of the wheeled toy, and

Fig. 4 a vertical sectional view through the wheeled toy, taken as on the line 4—4, Fig. 3.

I claim:

The ornamental design for a wheeled toy, substantially as shown.

EARL J. REIFF.
